WALTHER AKEMANN, OF ESSEN, GERMANY, ASSIGNOR, BY MESNE ASSIGNMENTS, TO
N. V. HAZEMEYER'S SIGNAL-APPARATEN, OF HENGELLO, NETHERLANDS.

TRAINING MECHANISM FOR GUNS.

Application filed November 16, 1920, Serial No. 424,522, and in Germany April 12, 1917.

This invention relates to mechanism for simultaneously controlling the aiming of a plurality of guns on one and the same target from a single observation point or controlling station.

The description which follows refers to the accompanying drawing, in which:

Figs. 1 and 2 are diagrams illustrating the principle of the invention, and
10 Figs. 3 to 6 represent three different embodiments of the invention, diagrammatically illustrated in Fig. 2.

The geometrical principles on which the invention is based will first be discussed.

15 When it is desired to simultaneously aim a plurality of guns of a coast defense station or a battleship, from a common observation point, account must necessarily be taken of the different locations of the guns with respect to said observation point.

The relation between the values entering into the problem will first be discussed with reference to the diagrams of Figs. 1 and 2.

In Fig. 1, which represents one observation point and one gun, both of which may be carried by a moving vehicle or vessel, A represents the observation point, A¹ the gun mount and A² the target. The difference in location is therefore represented by the line A—A¹, which includes, when extended, with the line A—A², connecting the observation point A with the target A², the angle designated α . The lines A—A¹ and A²—A¹ enclose the angle β , and the lines A—A² and A¹—A² the angle γ . The perpendicular from A¹ to line A—A² strikes said line in the point A³. There is also drawn through A¹ a line parallel to A—A², which includes, with the line A¹—A², as will be obvious, 40 an angle equal to the angle γ , included by A—A² and A¹—A². The equation for these angles α , β and γ , therefore is:

$$(1) \quad \gamma = \alpha - \beta$$

45 Also in the triangle A¹—A²—A³.

$$\tan \gamma = \frac{A^1 A^3}{A^2 A^3} \text{ or, since,}$$

$$A^1 A^3 = A A^1 \cdot \sin \alpha, \text{ and}$$

$$A^2 A^3 = A A^2 - A A^1$$

$$= A A^2 + A A^1 \cdot \cos \alpha, \text{ therefore:}$$

$$(2) \quad \tan \gamma = \frac{A A^1 \sin \alpha}{A A^2 + A A^1 \cdot \cos \alpha}$$

55 But A A¹ · cos α is always very small rela-

tively to A A², so that it is approximately true that

$$(3) \quad \tan \gamma = \frac{A A^1}{A A^2} \cdot \sin \alpha.$$

In further approximation, since naturally only very small angles are involved by γ , it can be assumed:

$$\gamma = \tan \gamma, \text{ and therefore,}$$

$$(4) \quad \gamma = \frac{A A^1}{A A^2} \cdot \sin \alpha,$$

that is to say, the angle γ is directly proportional to the difference of location and to the sin α , but inversely proportional to the distance of the target.

This relation is made use of in the following, in order to obtain mechanically, from the measured target distance A A², from the observed angle α , and from the known location difference A A¹, the angle γ , which is important for the determination of the lateral direction angle β to be given to the gun.

When a plurality of guns B¹, B², B³ are mounted upon a ship, see Fig. 2, and are to be controlled from one observation point B, so as to bear upon a target B⁴, such as a battleship, the equation (4) holds good for each of these guns, and therefore we have the following equations:

$$(5) \quad \gamma_1 = \frac{B B^1}{B B^4} \cdot \sin \alpha$$

$$(6) \quad \gamma_2 = \frac{B B^2}{B B^4} \cdot \sin \alpha$$

$$(7) \quad \gamma_3 = \frac{B B^3}{B B^4} \cdot \sin \alpha$$

that is to say, values of γ which bear the same relation to each other as the location differences between the observation point and the respective guns. Accordingly, in order to find the correct lateral sighting angles β_1 , β_2 , β_3 , for the individual guns, it is necessary to form the expressions:

$$(8) \quad \beta_1 = \alpha - \gamma_1$$

$$(9) \quad \beta_2 = \alpha - \gamma_2$$

$$(10) \quad \beta_3 = \alpha - \gamma_3$$

by diminishing the angle α , determined by the observer, through the angle γ , determined in each instance by equations (5) to (7). Since the angle γ can have either positive or

negative values according as to whether the angle α is greater or less than 180° , and according to the position of the observation point relatively to the guns, the equations 5 (8) to (10) really express that the lateral sighting angle β of each gun equals the algebraic sum of the angles α and γ .

The present invention therefore consists 10 in a lateral sighting or training mechanism for guns of the kind mentioned, in which a special intermediate transmission mechanism is provided between the transmitter at the observation point, and the receiving devices at the various gun stations, the function of 15 said intermediate transmission mechanism being first to mechanically derive the auxiliary angle γ from the angle α , obtained by sighting on the target, and secondly to mechanically form the algebraic sum of angles 20 α and γ , or to carry out one of the two said functions.

Referring now to Figs. 3 to 6, which are based upon the diagram of Fig. 2, Fig. 3 represents one embodiment of the invention, 25 while Fig. 4 is a section on line 4—4 of Fig. 3 looking from the left.

At the observation point B (Fig. 2) is a sighting telescope D (Fig. 3), rotatable about a vertical axis by a worm drive $d^1 d^2$, 30 and a hand wheel d^4 on the worm shaft d^3 , whereby it can be sighted on the target. On the shaft d^3 is also secured the armature of a transmitter d^5 , hereinafter called the main transmitter, of an electric long distance 35 transmission apparatus. The main transmitter d^5 is connected by conductors E with a receiver F, hereinafter called the auxiliary receiver and which serves to drive a mechanism by means of which the motion given 40 to the transmitter d^5 , and transmitted to the receiver F, is converted into the motions corresponding to the required lateral angular adjustment of the several guns, located at B^1 , B^2 and B^3 (Fig. 2). This mechanism, hereinafter called the intermediate transmission 45 mechanism, is constructed as follows:

On the armature shaft f^1 of the auxiliary receiver F are keyed two spur gears f^2 and f^3 , of which f^2 meshes with the toothed periphery g^1 of a drum G, having one of its front ends open and journalled in a fixed frame g^2 , in which is also journalled a graduated drum g^3 , provided on its periphery with a helical scale or graduations and which can 55 be adjusted by means of a hand wheel g^4 relatively to a mark g^5 , movable parallel to the axis of the drum g^3 , to different values of the distance $B B^4$, Fig. 2, between the target and the observation point. The drum 60 g^3 is positively connected, by means of a bevel gear and worm, with a worm wheel g^7 , freely rotatable about the hub g^6 of the drum G and rigidly connected with a bevel gear g^9 by a hollow shaft g^8 . A second similar bevel 65 gear f^5 is rigidly connected by its shaft f^6 ,

in alignment with the axis of the drum G, with a spur gear f^4 , which meshes with the second spur gear f^3 , mounted on the shaft f^1 and already mentioned. The ratios at the drives $f^2 g^1$ and $f^3 f^4$ are the same and are 70 so selected, in combination with the ratio between the telescope D and the transmitter d^5 , as well as between the latter and the receiver F that between the telescope D on the one hand and the drum G, as well as the shaft f^6 , 75 on the other hand, the transmission ratio is as 1:1.

The two bevel gears g^9 and f^5 form the sun wheels of a sun and planet drive, the planet gear g^{12} of which is loosely mounted 80 on a right-angled projecting arm g^{11} of a shaft g^{10} , coaxial with the drum G and passing through the hollow shaft g^8 and the drum hub g^6 . On the end of the shaft g^{10} , which projects into the drum G, is keyed a bevel gear g^{13} , which meshes with a bevel gear g^{14} , keyed on a shaft g^{15} , which is journalled within the drum G so that its axis coincides with a diameter of said drum and is screw-threaded at g^{16} for about half its length. 90 On this threaded portion g^{16} engages the nut h^1 , which is formed by one end of an arm H, lying in the axis of the drum and carrying at its other end a pin h^2 , on which is a block h^6 slidably guided in a guideway h^4 . 95 As the drum G rotates, said pin h^2 constitutes a crank-pin, having a crank-arm of variable length, which is determined by the distance of the axis of the arm H from the axis of the drum G. By rotation of the bevel gear g^{14} , 100 keyed on the spindle g^{15} , and the consequent displacement of the nut h^1 , the length of the crank-arm can be adjusted to various amounts, the arrangement being such that the crank-arm attains its greatest length 105 when the pointer g^5 indicates the lowest value of the corresponding distance graduation (drum g^3) and vice versa. Therefore, in order to make the length of the crank-arm inversely proportional to the distance 110 between observation point and target, it is only necessary, as will now be evident, to adjust the graduated drum g^3 to the desired distance value by means of the hand-wheel g^4 . 115 On account of the provision of the sun and planet drive $f^5 g^{12} g^9$, it is quite immaterial whether the drum G and shaft G^{15} revolve or whether it remains stationary. If the drum G does rotate, then, on account of the 120 equality of the transmission ratios of the spur gear drives $f^2 g^1$ and $f^3 f^4$, and on account of the same direction of rotation of the drum G and the bevel gear g^{13} , the latter must turn with the same angular speed and in the same direction as the drum G, as long as the hand-wheel g^4 is stationary. Since the bevel gear g^{14} and its shaft g^{15} take part in the rotation of the drum G and therefore have the same angular velocity as the gear 125 g^{13} in relation to the shaft g^{10} , the shaft g^{15} 130

cannot now be rotated on its axis by the bevel gear g^{14} . But when the hand wheel g^4 is turned, a proportional rotation of the shaft g^{15} takes place, which results in a corresponding displacement of the nut h^1 .

The guideway h^4 is in its turn itself movable, in a fixed guide h^3 , transversely to the direction of movement of the pin h^2 , thus forming, in combination with the arm H , adjustable longitudinally of the screw spindle g^{16} , a slide crank drive, which comprises a reciprocating portion (guide h^4) of variable stroke, and a rotary portion (pin h^2) of variable crank radius. In consequence of the construction described, the travel of the guide h^4 in its guideway h^3 , when the drum G is turned through a given angle, is proportional to the sine of said angle.

To the guideway h^4 is rigidly connected a rack h^5 extending parallel to the guideway h^3 and which meshes with a pinion i^1 keyed on a shaft J , on which are also mounted three bevel gears i^2 , corresponding in number to the guns to be sighted. Each of said gears meshes with another bevel gear i^3 , with which is positively connected, through a spur gear drive $i^4 i^5$, the one sun gear i^6 of a sun and planet drive $i^6 i^7 i^8$. The other sun gear i^9 of each of said drives is positively connected, by a bevel gear drive $i^{10} f^6$, with the auxiliary receiver shaft f^1 . The same ratio is given the bevel gears f^7 and i^{10} as the spur gears f^3 and f^4 . Each of the planet gears i^7 serves to drive an auxiliary transmitter i^9 , all three of which are connected to the main receivers (not shown) which belong to the individual guns. In order to obtain the proper direction of rotation, in accordance with the position of the respective gun station relatively to the observation point (Fig. 2), of each of the auxiliary transmitters i^9 and of the main receivers connected thereto, one of the three bevel gear pairs $i^2 i^3$ is so arranged that the driven gear i^3 must run in the opposite direction to the driven gear of the other two bevel gear pairs. Further, the difference in the distance of the individual guns from the observation point is taken care of by the proper selection of the transmission ratio of the spur gear drives $i^4 i^5$. This provides that when the shaft f^1 is rotated by the auxiliary receiver F , the sun gears i^6 undergo angular alterations which satisfy the equations (5) to (7), deduced for the angles γ_1 , γ_2 and γ_3 . Since also each of the three sun gears i^6 must turn, in the said rotation of the shaft f^1 , through an angle α , therefore angular alterations β_1 , β_2 and β_3 , which satisfy to the equations (8) to (10) are transmitted to the auxiliary transmitters i^9 .

Now, when a lateral sighting movement is to be transmitted from the observation point B , Fig. 2, to the guns located at the points B^1 , B^2 and B^3 —which movement is there used

either for automatic aiming of the guns or causes a suitable actuation of a mechanism adapted to indicate the lateral aiming,—the first thing is to communicate the distance B B^4 , obtained at the observation point B , to the operator of the intermediate transmitter apparatus. He then adjusts the drum g^3 , by turning the hand-wheel g^4 , Fig. 3, so that the pointer g^5 stands opposite the corresponding distance graduation line. In doing this, the planet gear g^{12} rolls on the bevel gear f^6 and turns the shaft g^{10} . The bevel gear g^{13} transmits this rotation to the bevel gear g^{14} and shaft g^{15} , and the nut h^1 of the arm H is displaced on the screw spindle g^{16} through a corresponding distance and the slide block h^6 , containing the crank pin h^2 , Fig. 4, slides in the guide h^4 until the pin h^2 has taken such a position that the crank radius, measured from its axis to the axis of the drum G , of the crank slide mechanism Hh^4 attains a value corresponding to the adjusted distance from the observation point to the target. If now the hand wheel d^4 is turned until the telescope D is sighted on the target, at which operation the telescope receives an angular alteration α , then the drum G and the bevel gear g^{13} , driven through the bevel gear drive $f^5 g^{12} g^9$, are turned in the same direction through the angle α , in consequence of the connection of the main transmitter d^6 with the auxiliary receiver F of the intermediate transmitter apparatus and of the transmission ratio 1:1 between the telescope D and the shaft f^6 as well as the drum G . Exactly the same angular alteration is imparted at the same time to the sun wheels i^6 of the three sun and planet drives $i^6 i^7 i^8$, appertaining to the individual guns, and to the arm H which partakes in the rotation of the drum G . The change in angle, transmitted by the crank slide mechanism Hh^4 and rack drive $h^5 i^1$ to the shaft J , is therefore proportional to sine α . In consequence of the rotation of the shaft J , the sun wheels i^6 , positively connected therewith, receive an angular alteration, determined as to amount and direction of rotation, by the arrangement of the bevel gear pairs $i^2 i^3$ and the transmission ratio of the spur gear drives $i^4 i^5$, which alteration as before stated, is equal to said angles γ_1 , γ_2 or γ_3 , which are to be algebraically added to the angle α , when the lateral sighting angles β_1 , β_2 or β_3 of the guns are to be obtained. This algebraic addition is performed by the sun and planet drives $i^6 i^7 i^8$, so that the auxiliary transmitters i^9 and the main receivers, (not shown), connected thereto through the switch M receive the prescribed angular alterations β_1 , β_2 or β_3 . Now each gun can be directly given the prescribed lateral direction according to the indications of the apparatus, connected to the main receivers and showing the lateral

sighting direction angle or by means of a device adapted to automatically direct the guns themselves.

Heretofore, it has been tacitly assumed that, during the rotation of the hand-wheel d^4 , that is during the operation of sighting proper, nothing changes in the adjustment of the graduated drum g^3 . However, this assumption can be abandoned without harm, because, if account is to be taken of a distance variation occurring during rotation of the hand-wheel d^4 , the operator serving the intermediate transmitting mechanism has only to make the necessary adjustment on the hand-wheel g^4 . In consequence of the disposition of the drum g^3 in the fixed frame g^2 and in consequence of the arrangement of the sun and planet drive g^9 g^{12} f^5 , he can, without leaving his place, always make the correct distance value adjustment, so that the correct indications are always transmitted to the receivers located at the guns.

The second embodiment of the invention, illustrated in Fig. 5 differs from the one just described in that on the shaft f^1 of the intermediate transmitting mechanism—the bevel gears f^7 and the sun and planet mechanisms i^8 i^7 i^6 , driven thereby, being omitted—an auxiliary transmitter f^8 is mounted which is connected by a conductor N , divided into three parallel branches n^1 , n^2 , n^3 , to a device P , indicating the angle α , for each of the three guns. In addition to these devices P , indicating the angle α , there is located at each gun a device P^1 for indicating the angles γ_1 , γ_2 and γ_3 , which are each fed by a special auxiliary transmitter i^9 . These transmitters i^9 are driven through bevel gears drives i^{11} i^{12} from the pinion shaft J , which is driven by the crank slide mechanism Hh^4 of the intermediate transmission mechanism. The bevel gear drives i^{11} i^{12} are so arranged and have such transmission ratios that the angular alterations imparted to the auxiliary transmitters i^9 , are equal to the angles γ_1 , γ_2 and γ_3 , which are to be algebraically added to the angle α , in order to obtain the lateral sighting angles β_1 , β_2 and β_3 of the guns. The devices P and P^1 are provided with pointers p^2 and p^3 by means of which the angle α and the angles γ_1 , γ_2 and γ_3 can be read on graduated discs. Furthermore, trailer pointers or following marks q^1 q^2 are arranged coaxially with the pointers p^2 and p^3 and revolvable independently of the same, of which one, q^1 , is driven by the planet gear q^3 of a sun and planet drive, the sun gears q^4 and q^5 of which are positively connected on the one hand with a circular rack q^6 , mounted on the gun carriage Q , and on the other hand through spur gears q^8 , q^9 and q^{10} with a hand-wheel q^7 , serving to actuate the other following mark q^2 . For directing the gun carriage Q , another hand-wheel q^{11} is provided, which is positively connected by a bevel gear drive

with a pinion q^{12} meshing with the circular rack q^6 .

In consequence of the described arrangement at each gun the following mark q^1 belonging to the pointer p^2 of the dial P , when the respective carriage Q is turned by the hand-wheel q^{11} , must receive a displacement proportional to said turning movement, as long as the corresponding sun gear q^4 of the sun and planet drive q^4 , q^8 q^5 and positively connected to the hand-wheel q^7 remains stationary. On the other hand, when said hand-wheel q^7 is turned, the sum or difference of the rotations of the sun gears q^4 and q^5 must be transmitted to the mark q^1 . Consequently the latter, after it has been placed over the pointer p^2 by a rotation of the hand-wheel q^{11} , must take a position different from that of the pointer p^2 , as soon as the mark q^2 has been brought into coincidence with its pointer p^3 by means of the hand wheel q^7 . It is however, only by a second turning of the hand-wheel q^{11} that the mark q^1 is definitely brought into coincidence with its pointer p^2 , and at the same time the carriage Q is brought into the position corresponding to the lateral sighting angles β_1 , β_2 or β_3 and prescribed by the algebraic sum of the angles α and γ_1 , γ_2 or γ_3 .

In using the apparatus of Fig. 5, one begins with the assumption that all the guns Q are adjusted to the lateral direction in which is $\beta=0$ and that the pointers p^2 p^3 and the corresponding marks q^1 , q^2 coincide at all the indicators P and P^1 .

Now when by directing the telescope on the target, the angular alteration α is transmitted to the indicators P , the pointers p^2 assume the corresponding positions, equal to each other, while the pointers p^3 receive displacements corresponding to relatively different values γ_1 , γ_2 and γ_3 . Thereupon, at each gun, by turning the hand-wheel q^{11} , the carriage Q is turned about its vertical axis in a direction which causes the corresponding following mark q^1 to turn in the same direction as the pointer p^2 until it comes into coincidence with this latter. By then turning the hand-wheel q^7 coincidence of the mark q^2 with the pointer p^3 is established. Since in so doing, the planet gear q^3 , rolling on the stationary bevel gear q^4 , causes a displacement of the marks q^1 , the coincidence of the pointer p^2 and the mark q^1 is again lost, but is restored by again turning the hand-wheel q^{11} . Since, in the last mentioned adjustment of the mark q^1 the coincidence of the mark q^2 and the pointer p^3 does not undergo any change, the carriage Q of each gun undergoes a rotation corresponding to the size of the angle γ_1 , γ_2 and γ_3 , so that now the lateral directing angle β_1 , β_2 and β_3 is actually imparted to each gun, which angle represents the algebraic sum of the angular alterations α and γ_1 , γ_2 and γ_3 .

If the crank slide drive Hh^4 is brought into direct positive connection with the driving member d^4 of the main transmitter d^3 , the arrangement will be that shown in Fig. 6. This 5 differs from those hereinbefore described further in that an auxiliary transmitter i^{13} is coupled to the pinion shaft J , its function being to feed an auxiliary receiver i^{14} , serving, in combination with the auxiliary receiver F , 10 to drive the intermediate transmission mechanism. The receiver i^{14} is positively connected with a shaft i^{15} , on which are secured the bevel gears i^2 , shown also in Fig. 3, which drive the sun gears i^6 of the sun and planet 15 drives $i^6 i^7 i^8$. The auxiliary transmitters i^9 are positively connected with the planet gears i^7 in exactly the same way as in the arrangement of Fig. 3. Accordingly, the arrangement of Fig. 6 differs from that of Fig. 3, as 20 far as its operation is concerned, only in the fact that the adjustment of the scale drum g^3 for variable distances must be made at the observation point. It can therefore be worked by the same operator who has charge 25 of the directing of the telescope D on the target. A special operator for the intermediate transmission mechanism is therefore not required.

Having thus described the invention, what 30 is claimed is:

1. Apparatus for imparting the lateral direction to a plurality of guns from a distant observation point, comprising a telescope at said point, an electric transmitter mechanically 35 connected to said telescope to rotate therewith, an electric receiver electrically connected to said transmitter, an auxiliary electric transmitter for each gun operatively connected to a corresponding receiver at each gun, 40 which controls the directing thereof, and a transmission gearing between said first named receiver and said auxiliary transmitters including a rotatable element positively connected to said first named receiver and adjustable 45 in accordance with the distance of the target from the observation point and an element positively connected to said auxiliary transmitters and movable in a straight line, said elements constituting a slide crank device forming part of said transmission gearing. 50

2. An apparatus for imparting the lateral training to a plurality of guns from a distant observation point comprising a sighting device disposed at said observation point, gun 55 training mechanism at each gun to be actuated in dependence on the lateral movements of said sighting device, an intermediate transmitter apparatus, said apparatus embodying a slide crank device, an adjustable 60 crank forming a part of said crank device, means including a sun and planet gear for operating said adjustable crank, an electrical distance control connecting said last mentioned means to said sighting device, said adjustable crank being rotatable proportionally to the lateral sighting angle of said sighting device, an indicating device provided with a stationary support and means operatively connecting said indicating device to one gear 65 of said sun and planet gear and electrical distance control means connecting said intermediate transmitter apparatus to said guns. 70

3. An apparatus for imparting lateral direction to a plurality of guns from a distant 75 observation point comprising a sighting device located at said point, an intermediate transmitter apparatus, distance adjusting mechanism connecting said sighting device to said intermediate transmitter apparatus 80 and gun training mechanism at each gun, each mechanism embodying receivers each provided with a pointer, one of said receivers being adjustable in accordance with the lateral adjustment of said sighting device, said 85 other receiver being adjusted by said intermediate transmitter apparatus, a gauge mark associated with the pointer of each receiver, training mechanism for each gun, a sun and planet gearing operatively connected with 90 said training mechanism, one of said gauge marks being operatively connected to one of the gears of said sun and planet gearing and means operatively connected to said sun and planet gearing for moving the other of 95 said gauge marks whereby each gun may be trained laterally in accordance with the readings of its associated two receivers.

The foregoing specification signed at Essen, Germany, this 16th day of June, 1920.

DR. WALTHER AKEMANN.
